CLAIM

The ornamental design for a modeling device unit, as shown and described.

DESCRIPTION

FIG. 1 is a perspective view of a modeling device unit. FIG. 2 is a bottom elevation view of the modeling device unit of FIG. 1, viewed in direction 2-2 in FIG. 1. FIG. 3 is a top elevation view of the modeling device unit shown in FIG. 1, viewed in direction 3-3 in FIG. 1. FIG. 4 is a front elevation view of the modeling device unit shown in FIG. 1, viewed in direction 4-4 in FIG. 3; and, FIG. 5 is a rear elevation view of the modeling device unit shown in FIG. 1, viewed in direction 5-5 in FIG. 3.

1 Claim, 5 Drawing Sheets
